Edward Mullen and Ross Harris, Detroit, Mich.,
assignors to Mechanical Handling Systems,
Inc., Detroit, Mich., a corporation of Michigan

Application October 14, 1946, Serial No. 133,920

Term of patent 14 years

(Cl. D14—3)

To all whom it may concern:

Be it known that we, Edward Mullen and Ross Harris, citizens of the United States, residing at 13542 Cherrylawn and 120 Virginia Park, respectively, Detroit, county of Wayne, and State of Michigan, have invented a new, original, and ornamental Design for Tank Trailers, of which the following is a specification.

In the accompanying drawings which form a part of this specification, Fig. 1 is a side elevation of a tank trailer embodying this design, Fig. 2 is a rear end elevation of such trailer, and Fig. 3 is a top perspective view taken from the front of such trailer.

We claim:

The ornamental design for a tank trailer, as shown.

EDWARD MULLEN.
ROSS HARRIS.
